CLAIM

The ornamental design for a bench top gripping device, as shown and described.

DESCRIPTION

FIG. 1 is a top perspective view of a bench top gripping device showing our new design;

FIG. 2 is a bottom perspective view thereof;

FIG. 3 is a top plan view thereof;

FIG. 4 is a bottom plan view thereof;

FIG. 5 is a side elevational view thereof; and,

FIG. 6 is a side sectional view taken through the diameter thereof.

1 Claim, 2 Drawing Sheets
